The ornamental design for a clip for a cord management system, as shown and described.

DESCRIPTION

The present application relates to the following Patents and Applications:
to U.S. utility patent application Ser. No. 12/761,326, filed Apr. 15, 2010, (now abandoned),
to U.S. design patent application Ser. No. 29/368,746, filed Aug. 27, 2010 (now U.S. Pat. No. D636,659),
to U.S. design patent application Ser. No. 29/368,755, filed Aug. 27, 2010, (now U.S. Pat. No. D667,291),

to U.S. design application Ser. No. 29/388,372, filed Mar. 28, 2011, (now U.S. Pat. No. D645,332),
to U.S. design application Ser. No. 29/401,643, filed Sep. 11, 2011,
to U.S. design application Ser. No. 29/401,359, filed Sep. 11, 2011, and
to U.S. design application Ser. No. 29/401,930, filed Sep. 16, 2011.

FIG. 1 is a perspective view of an embodiment of our new design of a clip for a cord management system.

FIG. 2 is a view of a first side of the embodiment of FIG. 1. FIG. 3 is a view of a second side of the embodiment of FIG. 1.

FIG. 4 is a view of a third side of the embodiment of FIG. 1. FIG. 5 is a view of a fourth side of the embodiment of FIG. 1. FIG. 6 is a view of a fifth side of the embodiment of FIG. 1. FIG. 7 is a view of a sixth side of the embodiment of FIG. 1. FIG. 8 is another perspective view of the embodiment of FIG. 1 provided for illustrative purposes, the perspective view illustrating the embodiment when used in conjunction with an object.

FIG. 9 is another embodiment of our new design of a clip for a cord management system, the only difference between this embodiment and the embodiment of FIG. 1 being the specific shape of the cord retention portion, it being understood that all other portions of the clip are the same as those of the embodiment of FIG. 1; and,

FIG. 10 is another embodiment of our new design of a clip for a cord management system, the only difference between this embodiment and the embodiment of FIG. 1 being the specific shape of the cord retention portion, it being understood that all other portions of the clip are the same as those of the embodiment of FIG. 1.

The broken lines represent environment and form no part of the claim.
